UNITED STATES PATENT OFFICE.

GEORGE H. GILMAN, OF BOSTON, MASSACHUSETTS.

DRILLING MACHINE.

Application filed June 5, 1920. Serial No. 386,868.

My invention relates to drilling machines and particularly, but not exclusively to those for drilling rock and includes among other things a fluid pressure motor which, although particularly adapted to drilling machines, is of general application.

My invention will be best understood from the following specification when read in connection with the accompanying drawings showing one specific embodiment of my invention submitted for illustrative purposes, while the scope of my invention will be more particularly pointed out in the appended claims.

15 In the drawings:

Fig. 1 shows for the most part in longitudinal section, a rock drill embodying my invention;

Fig. 2 is a fragmentary section on the line 20 2—2 of Fig. 1;

Fig. 3 is a section similar to Fig. 2 with the valves omitted;

Fig. 4 is a section on the line 4—4 of Fig. 1;

Fig. 5 is a section on the line 5—5 of Fig. 1;

Fig. 6 is a section on the line 6—6 of Fig. 1;

Fig. 7 is a section on the line 7—7 of Fig. 1;

Fig. 8 is a section on the line 8—8 of Fig. 1; and

Fig. 9 shows in perspective on an enlarged scale a portion of the mechanism for holding the water tube in position.

The drilling machine submitted, showing a specific embodiment of my invention, comprises a casing having a cylinder member 1 and a front head structure 2. Mounted for reciprocation in the cylinder is a piston 3 provided with a hammer bar 4 extending into the front head structure and adapted to operate by impact on the polygonal end 5 of the drill steel 6, the end of the steel being received by a polygonal recess in a chuck 7, and the latter being mounted for rotation in the front head structure. Besides operating the steel by impact I also prefer to operate it by imparting thereto from the piston a rotary movement and for this purpose I provide suitable mechanism which will now be described.

Rearwardly of the cylinder and preferably in the rear head structure which comprises the block 8, I mount a pair of ratchet wheels 9 and 10 to which are secured rifle

bars 11 and 12 which extend through the cylinder into the piston and respectively engage the rifle nuts 13 and 14 carried by said piston. The rifle bars 11 and 12 just referred to are, as clearly illustrated by Fig. 1, arranged in telescopic relation, the outer rifle bar 11 being secured to the ratchet ring 10 and the inner rifle bar 12 being secured to the ratchet ring 9. On the exterior surface of the rifle bar 11 are formed grooves 15 which cooperate with lugs 16 on the rifle nut 13 while on the exterior surface of the rifle bar 12 are formed grooves 17 cooperating with the lugs 18 formed on the interior surface of the rifle nut 14. The hammer bar 4 extends into and is surrounded by the chuck. For connecting the hammer bar to the chuck, on the exterior surface of the hammer bar I provide grooves 19 cooperating with lugs 20 formed on the interior surface of the chuck. Preferably, the grooves 15 and 17 are formed with the same pitch and are oppositely inclined, while the grooves 19 are parallel to the axis of the piston and hammer bar. The ratchets 9 and 10 cooperate with suitable pawls 21 held in engagement therewith by spring pressed detents 22 the ratchets and pawls being so arranged that both rifle bars may rotate in the same direction, rotation in the opposite direction, as will be obvious, being prevented by the pawls.

When the piston is reciprocated by motive fluid admitted and exhausted in a manner hereinafter described, the piston on the rearward stroke, is rotated by the rifle bar 12 in the direction indicated by the arrows in Fig. 1 and on the forward stroke is rotated in the same direction by the rifle bar 11. When the piston rotates, it rotates the chuck and as the pitch of the grooves 15 and 17 is the same, the chuck is rotated during each stroke of the piston in the same direction and through the same angle.

For operating the piston I provide the valve 23, which preferably, as illustrated by Fig. 2, is provided with an internal conduit 24 making the valve of the shape which I prefer to term "tubular".

The valve extends longitudinally of the cylinder and communicates therewith through passages 25 and 26, which connect the cylinder and valve chambers adjacent the corresponding opposite ends thereof. Leading to the valve chamber and communicating with the internal conduit 24 of

the valve is a motive fluid supply conduit 27, these conduits forming part of the inlet connection adapted alternately to be placed in communication with the opposite ends of the cylinder by the valve. When the valve is in the position shown by Fig. 1, the motive fluid flows through the interior of the valve and enters the passage 26 passing into the front end of the cylinder to drive the piston rearwardly and when the valve is in its opposite position, the passage 26 is cut off from communication with the inlet connection and motive fluid is supplied to the passage 25 to admit the same to the rear end of the cylinder to drive the piston forwardly.

For exhausting the ends of the cylinder, I provide on the exterior of the valve adjacent the ends thereof, grooves 28 and 29 and respectively cooperating therewith, grooves 30 and 30' formed interiorly of the valve casing and providing exhaust chambers. The chambers formed by the grooves 30 and 30' are maintained in constant communication with the atmosphere by means of conduits 31 which are maintained in constant communication with the grooves 30 and 30' by means of slots 32 and 33 respectively formed in the valve casing sleeves and body of the main cylinder portion. When the valve is in position illustrated by Fig. 1, the groove 28 of the valve connects the passage 25 with the groove 30 and thus exhausts the rear end of the cylinder. When the valve is in its opposite position as illustrated by Fig. 2, the groove 29 connects the passage 26 with the groove 30' and thus exhausts the forward end of the cylinder.

For providing additional exhaust means, adjacent the central portion of the cylinder I provide radial passages 35 which communicate with the passages 31. The passages 35, as will be understood by those skilled in the art are adapted to be uncovered by the piston as it approaches the end of its stroke to permit the motive fluid behind it to exhaust.

For moving the valve, I provide the same with an enlarged portion 36 which provides oppositely facing surfaces 37 and 38. Communicating with the surface 37 is a kicker port 42 which opens into the cylinder at 39 and communicating with the surface 38 is a kicker port 41 which opens into the cylinder at 40. As the piston reciprocates, it alternately covers and uncovers the ends 39 and 40 of the kicker ports and thus alternately admits and exhausts motive fluid to the surfaces 37 and 38 to move the valve.

Preferably, I provide means for locking the valve when it has been moved to the opposite ends of its travel. For this purpose I form the valve to provide oppositely facing surfaces 43 and 44, preferably smaller

in area than the surfaces 37 and 38 and respectively facing in the same direction as the latter and being located between them and the corresponding ends of the valve. To the surfaces 43 and 44 I admit motive fluid to lock the valves in position. For this purpose, I provide the valve with radial passages 45 and 46 communicating with the interior conduit thereof and adapted to be alternately opened and closed by the valve, when moved by the motive fluid admitted against the surfaces 37 and 38. For exhausting the motive fluid from the surfaces 43 and 44 I provide passages 47 and 48, one end of these respectively being in constant communication with the valve chamber adjacent the surfaces 43 and 44 and the other ends respectively being adapted alternately to be placed in communication with the exhaust chambers 30 and 30'. For controlling the exhaust passages 47 and 48, the same respectively are formed to terminate on the interior surface of the valve casing between the opposite annular grooves 49 and 56, and the adjacent grooves 30 and 30'. Thus, when the valve is in the position shown by Fig. 1, the exhaust passage 47 is in communication with the exhaust, while the exhaust passage 48 is closed and when the valve is moved to its opposite position, the exhaust passage 47 is closed and 48 open.

The valve casing is formed by means of two telescopic sleeves 50 and 51, held in assembled relation by means of the spring 52 which abuts the shoulder 54 formed on the inner member 51 of the valve casing at one end and the head block 8 at the other end. The valve casing thus formed, is provided on the interior thereof with annular grooves 49, 30', 53, 54, 55 and 56. The annular grooves 49 and 56 respectively connect with the opposite cylinder portions through the passages 25 and 26 and the grooves 53, 54, and 55 respectively form chambers for the shoulder portions of the valve forming the surfaces 43, 37, 38 and 44.

The operation of the valve and associated mechanism is as follows: With the parts in the position shown by Fig. 1, the motive fluid flows from the rear end to the forward end of the valve through the internal bore 24 into the grooves 56 of the valve casing and hence into the forward end of the cylinder through the passage 26 forcing the piston rearwardly. The fluid at the rear of the piston exhausts through the exhaust port 35 into the conduits 31 and discharges to the atmosphere, while at the same time and after the passage 35 is closed, motive fluid also exhausts through the passage 25 around the reduced portion 28 of the valve into the chamber 30 and hence to the exhaust passage 31 by way of the slots 32 and 33 whence it passes to the atmosphere. In this position

of the valve, the air from the locking surface 43 is exhausted through the passage 47 which at this time is open to the exhaust, while motive fluid is admitted to the surface 5 38 to hold the valve in position through the passage 46 which at this time is open. When the front end of the piston uncovers the end 39 of the kicker port 42, motive fluid is admitted from the cylinder through 10 the passage 42 to act on the surface 37 of the valve to throw it forwardly. As the valve moves forwardly, the passage 46 is cut off and immediately after this, the forward end of the passage 48 is opened to 15 exhaust the motive fluid from the surface 44. The valve thus being moved and held in the position shown by Fig. 2, motive fluid is admitted to the rear end of the cylinder through the passage 25 and exhausted from 20 the front end by means of the passage 26 and exhaust passage 35. The piston now moves forwardly and when the piston uncovers the end 40 of the kicker port 41, motive fluid is admitted to the surface 38. 25 of the valve to throw it rearwardly. The rearward movement of the valve closes the exhaust port 48 leading from the surface 44 and opens the inlet port 46 which admits fluid to the surface 44 to hold the valve in 30 its rearward position. The cycle of operation is now repeated.

The head block 8 before referred to is preferably provided with a longitudinal bore 60 to receive a manually operated throttle valve 61, the end of the bore 60 being adapted to be connected with the source of motive fluid for supplying motive fluid for operating the machine.

Through the valve 61 is formed a longitudinal passage 62 having a transverse passage 63 communicating therewith, the latter being adapted to connect in the position of the valve shown by Figs. 1 and 2 with the passage 27 in the valve casing. The exhaust 40 passages 31 in the valve casing communicate with the bore 60 through ports 64 which in the position of the valve shown by Figs. 1 and 2 are in communication with the atmosphere by way of passages 65 formed in 45 the valve and communicating passages 66 formed in the head block. In the same plane as the ports 64 are passages 67 formed in the valve and communicating with the live motive fluid passage 62. If the valve is 50 turned counterclockwise, as viewed in Fig. 1, the passages 65 are moved out of communication with the ports 64 and the passages 67 are placed in communication with said ports. This prevents operation of the 55 machine because the exhaust is virtually closed and the motive fluid now admitted to the exhaust passages 31 flows through passages 68 connecting the passages 31 with the rearward end of the chuck chamber 69. 60 Motive fluid thus admitted to the rearward

end of the chuck chamber passes to the forward end thereof by way of the grooves 19 formed on the exterior surfaces of the hammer bar and the space between the hammer bar and chuck. From the forward end of the chamber the motive fluid passes into the bore 70 of the drill steel and flows to the cutting end thereof to sludge the hole.

For supplying water to the hollow drill steel, I provide a tube 71 supported in the base of the handle member 73 and extending through the machine to the front end thereof where it enters the bore of the steel. Communicating by means of a passage 82 with a chamber 75 formed in the handle member is a water supply connection 74.

For supporting the tube I provide a member having a base portion 76 and the conical sleeve portion 77. The sleeve member is split or slotted as indicated at 79, and is cut away adjacent its juncture with the base 76 to form an annular groove 78. The slots 79 and grooves 78 render the sleeve portion flexible. In screw threaded engagement with the chamber 78 is a plug 80 provided with a conical recess 81, the taper of which corresponds to the taper of the conical sleeve 77. When the plug 80 is screwed into position, the conical recess thereof clamps the sleeve against the tube and holds the latter firmly in position. The base portion 76 is adapted to be forced by the plug 80 against the packing 82 to compress the same and form a tight joint about the tube to prevent entrance of water into the cylinder chamber. The water admitted to the chamber 80 finds its way through the slots 79 into the rear end of the recess 81 of the plug whence it passes into the bore of the tube 71 and finds its way into the hollow drill steel.

It will be observed that I have provided a casing, part of which receives motive fluid for acting upon the pressure faces of the piston to effect linear movement of the piston and that this part of the casing which I prefer to call the "piston chamber" and which, in the submitted embodiment of my invention, is the chamber in which the large rear head of the piston reciprocates, has therein the members 11 and 12 which are mounted directly on the casing for rotation. Although I have submitted one specific embodiment of my invention for illustrative purposes, it is to be understood that I am not limited thereby to the specific mechanical details or arrangement of parts thereof, but that extensive deviations therefrom may be made without departing from the spirit of my invention.

Claims:

1. In a drilling machine, a cylinder, a piston in said cylinder, a chuck, a plurality of rifle bars cooperating with said piston, separate means connecting said piston to

- 4
1. said rifle bars and chuck, at least two of said separate means providing an oblique cam and a cooperating follower and means for reciprocating said piston, whereby said chuck is rotated through said connecting means during each direction of reciprocation of said piston.
2. In a drilling machine, a cylinder, a piston in said cylinder, a chuck, a plurality of rifle bars cooperating with said piston, separate means connecting said piston to said rifle bars and chuck, at least two of said separate means providing an oblique cam and a cooperating follower, and means for reciprocating said piston, whereby said chuck is rotated at the same speed in the same direction through said connecting means during each direction of reciprocation of said piston. 70
- 10 3. In a drilling machine, a cylinder, a piston therein, a chuck, a plurality of rifle bars cooperating with said piston, each of said separate means providing a surface and a cooperating follower and each of said surfaces being angularly disposed relatively to each of the other surfaces, and means for reciprocating said piston, whereby said chuck is rotated through the connecting means during each direction of reciprocation of the piston. 75
- 15 4. In a drilling machine, a cylinder, a piston therein, a chuck, a plurality of rifle bars cooperating with said piston, oppositely oblique grooves and followers connecting the respective rifle bars to said piston, a groove parallel to the axis of said piston and a cooperating follower connecting said chuck to said piston, and means for alternately preventing rotation of said rifle bars on opposite strokes of said piston, whereby said piston is rotated during each direction of reciprocation of said piston. 80
- 20 5. In a drilling machine, a cylinder, a piston therein, a chuck, a plurality of rifle bars cooperating with said piston, separate means connecting said piston to said rifle bars and chuck, at least two of said separate means providing an oblique cam and a cooperating follower and means for reciprocating said piston, whereby said chuck is rotated in the same direction through said connecting means during each direction of reciprocation of said piston. 85
- 25 6. In a drilling machine, a cylinder, a piston therein, a chuck, a plurality of rifle bars cooperating with said piston, each of said separate means providing a surface and a cooperating follower and each of said surfaces being angularly disposed relatively to each of the other surfaces, means for reciprocating said piston, and the angles between said surfaces being such that said chuck is rotated at the same speed in the same direction through the connecting means during each direction of reciprocation of the piston. 90
- 30 7. In a drilling machine, a cylinder, a piston therein, a chuck, a plurality of rifle bars cooperating with said piston, separate means connecting said piston to said rifle bars and chuck, each of said separate means providing a surface and a cooperating follower and each of said surfaces being angularly disposed relatively to each of the other surfaces, means for reciprocating said piston, and the angles between said surfaces being such that said chuck is rotated at the same speed in the same direction through the connecting means during each direction of reciprocation of the piston. 95
- 35 8. In a drilling machine, a cylinder, a piston therein, a chuck, a plurality of rifle bars cooperating with said piston, oppositely oblique grooves and followers connecting the respective rifle bars to said piston, a groove parallel to the axis of said piston and a cooperating follower connecting said chuck to said piston, and means for alternately preventing rotation of said rifle bars on opposite strokes of said piston, whereby said piston is rotated at the same speed in the same direction during each direction of reciprocation of said piston. 100
- 40 9. In a drilling machine, a cylinder, a piston therein, a chuck, a plurality of rifle bars cooperating with said piston, oppositely oblique grooves and followers connecting the respective rifle bars to said piston, a groove parallel to the axis of said piston and a cooperating follower connecting said chuck to said piston, and means for alternately preventing rotation of said rifle bars on opposite strokes of said piston, whereby said piston is rotated at the same speed in the same direction during each direction of reciprocation of said piston. 105
- 45 10. In a drilling machine, a cylinder, a piston therein, a chuck, a rifle bar, a second rifle bar surrounding said first rifle bar, both of said rifle bars extending into said piston, means comprising grooves and followers connecting said piston to each of said rifle bars and to said chuck, and means for alternately preventing rotation of said rifle bars on opposite strokes of said piston to cause the chuck to rotate. 110
- 50 11. In a drilling machine, a cylinder, a piston therein, a chuck, a rifle bar, a second rifle bar surrounding said first rifle bar, both of said rifle bars extending into said piston, means comprising grooves and followers connecting said piston to each of said rifle bars, and means for preventing rotation of one rifle bar on one stroke of said piston and of the other rifle bar on the opposite stroke whereby said piston is rotated during each stroke in the same direction. 115
- 55 12. In a drilling machine, a casing, a ham- 120
- 60 13. In a drilling machine, a cylinder, a piston therein, a chuck, a rifle bar, a second rifle bar surrounding said first rifle bar, both of said rifle bars extending into said piston, means comprising grooves and followers connecting said piston to each of said rifle bars, and means for preventing rotation of one rifle bar on one stroke of said piston and of the other rifle bar on the opposite stroke whereby said piston is rotated during each stroke in the same direction. 125
- 65 14. In a drilling machine, a casing, a ham- 130

mer piston in said casing, said hammer piston having a hammer bar, a pair of rifle bars; and means for causing said hammer piston to rotate said chuck during each direction of reciprocation of said hammer piston comprising slip-joint connections between said hammer bar and chuck and between said piston and rifle bars.

13. In a drilling machine, a cylinder, a hammer piston in said cylinder, a chuck, and means including a plurality of rifle bars for causing said piston to rotate said chuck during each direction of reciprocation of said piston comprising slip-joint connections be-

tween said hammer piston and chuck and between said hammer piston and each of said rifle bars.

14. In a drilling machine, a casing, a piston 3 having the hammer bar 4, a chuck connected to said hammer bar, rifle bars 11 and 20 12 having a cam connection with said hammer piston, and intermittent grip devices 9 and 10 connecting said rifle bars respectively with said casing.

In testimony whereof, I have signed my name to this specification.

GEORGE H. GILMAN.
